SLIP JACKET

Harold William Hershey, Brighton, N. Y.

Application July 31, 1947, Serial No. 765,040

4 Claims. (Cl. 22—112)

1

The present invention relates to slip jackets such as are used for holding sand molds, after the flask has been removed, and while the casting is being made.

Sand molds are usually either straight or tapered, that is, they are made either with vertical sides or with sides converging toward the top of the mold. Slip jackets are open-ended so as to be readily slipped on or removed from the molds. They are usually made to fit the type of mold, which is to be held, either straight or tapered; and a straight-type jacket is not suited for use in holding a tapered mold, or vice versa. In some cases, the slip jackets are made in one piece. Other types of slip jackets have their sides welded or bolted together. All of these types of slip jackets are inflexible. They must be made precisely to fit a given size and type of mold. In some cases, slip jackets have been made, however, with their sides hinged together at one corner and held together at another corner by springs and bolts. This construction permits of easily positioning of the jacket on the mold or removing it therefrom, but like the jackets first described is relatively inflexible and costly.

A primary object of the present invention is to provide a slip jacket that will be relatively cheap and that can readily and quickly be put on or taken off of a mold.

Another object of the invention is to provide a slip jacket that is capable of use on either a straight-sided or a tapered mold and that will accommodate itself to either type of mold.

Still another object of the invention is to provide a slip jacket which can quickly and easily be assembled for use, but which, when disassembled, is in knocked-down condition and will occupy a minimum of space in storage or when being shipped.

Still another object of the invention is to provide a knock-down type slip jacket of such construction that any size end walls may be assembled with any dimension side walls, to make quickly practically any size and shape of slip jacket, to fit any size and shape of mold.

Other objects of the invention will be apparent hereinafter from the specification and from the recital of the appended claims.

In the drawings:

Fig. 1 is a plan view of a slip jacket made according to one embodiment of this invention;

Fig. 2 is a side elevational view of this slip jacket showing in full lines the positions which the sides occupy when the jacket fits over a straight-sided mold, and in dotted lines the posi-

2

tions which the sides occupy when the jacket fits over a tapered mold;

Fig. 3 is a view looking at the slip jacket from one end, showing the parts in the positions which they occupy when fitting over a straight-sided mold;

Fig. 4 is a fragmentary view looking in the same direction, but showing the parts in the positions which they occupy when the slip jacket fits over a tapered mold;

Fig. 5 is a transverse sectional view, illustrating how the parts of the jacket are assembled; and

Fig. 6 is a corresponding view showing the assembly completed and the parts locked together.

Referring now to the drawings by numerals of reference, there is shown a rectangular-shaped slip jacket comprising two side plates 10 and two end plates 11. The inside surfaces of all of these plates, which are the surfaces which seat against the sides of the mold, are plane. The outside surfaces of the plates are also generally plane. The outside surfaces of the plates 10, however, are formed with three parallel, longitudinal reinforcing ribs 12, 12' and 12'' and with a plurality of joining, diagonally extending reinforcing ribs 13. The longitudinal ribs 12' are intended to be opposite the parting line of the mold, while the longitudinal ribs 12 and 12'' are somewhat below the top and somewhat above the bottom, respectively, of each plate 10.

Each side plate 10 is cut at its opposite ends at both top and bottom to provide the endwise projecting tongues 14. The ends 16 of each side plate 10 above the tongues 14 are inclined to the vertical, while the ends 15 of each such plate below the tongues 14 are vertical, that is, perpendicular to the tops and bottoms of the plates. Each tongue 14 has a generally plane outside surface that has formed thereon, at a point in line with rib 12' but spaced therefrom, an outwardly projecting locking lug 20. Each locking lug is slabbed off at one end as denoted at 21 (Fig. 5) and is rounded on the end adjacent rib 12' as denoted at 22. Each lug is drilled at an angle of about 45 degrees, as denoted at 24 (Fig. 5) to provide a threaded hole which is adapted to receive a locking screw 25. These screws have conical inner ends 26 for a purpose which will appear hereinafter.

Each end plate 11 is provided with parallel, longitudinally extending ribs 31, 31' and 31'' (Fig. 3). The upper and lower ribs 31 and 31'' are spaced somewhat down from the top and somewhat above the bottom, respectively, of the end plate. They extend for the full length of the

plate and are joined to, or are integral with vertical ribs 32 and 32' which lie at the extreme ends of the end plates and extend between the horizontal ribs 31 and 31''. The central horizontal rib 31' lies midway between the ribs 31 and 31'' at approximately the parting line of the mold. Diagonal ribs 33 connect the several horizontal ribs.

Each end plate 11 is formed with two slots 34 adjacent its opposite ends, respectively. These extend for the greater portion of the height of the end plate. They are of sufficient height to receive the tongues 14 and of sufficient width to permit the tongues with their lugs 20 to be passed readily therethrough.

One side wall 35 of each slot 34 is vertical. The upper half of the other side wall 36 of this slot is also vertical and is parallel to the side wall 35, but the lower half of this side wall is inclined to the vertical and diverges from the side wall 35 from the midpoint in the height of the slot to the bottom thereof, as clearly shown in Figs. 3 and 4.

Each rib 31' terminates at its opposite ends at the walls 35 of the slots 34, and is formed at each end with an enlarged abutment portion 37 which has a plane-end face 38 lying in the plane of the side wall 35 of the adjacent slot 34. The abutments 37 form seats or anvils against which the inner ends 26 of the thumb screws 25 are adapted to seat.

Figs. 5 and 6 show how a side plate 10 may be assembled with an end plate 11, thus illustrating how the four sides may be assembled to form a slip jacket. The plates 10 and 11 are assembled, of course, with their inside plane surfaces facing inwardly and their tops uppermost. With two plates 10 and 11 held in these positions, a tongue 14 of plate 10 is passed through a slot 34 of plate 11. As stated, each slot 34 is somewhat wider than the tongue and its lug 20. After the lug has been passed through the slot, the plate 10 is moved laterally to the position shown in Fig. 6, causing plate 11 to seat in the recess 23 formed in plate 10 between lug 20 and rib 12'. A thumb screw 25 is then threaded into the lug 20 and against the surface 38 of abutment 37 until the plate 10 is firmly locked against the side 36 of the slot, and plate 11 is held firmly against the end of rib 12' of plate 10. In this same way, each side plate is assembled with its adjacent end plate to form the slip jacket shown in Fig. 1.

In use, the slip jacket is simply passed over the mold after the flask has been removed therefrom. If it is a straight-sided mold, the plates 10 and 11 remain vertical as they slip down over the mold. If the mold is tapered, the side plates 10 and end plates 11 rock on the curved end surfaces of the lugs 20 and on the conical ends 26 of the screws 25 to incline inwardly and assume the shape of the mold. The positions assumed by the end plates for a tapered mold are shown in dotted lines at 11' in Fig. 2 and the positions assumed by the side plates for this type mold are shown in Fig. 4. The plates 11 can tilt until their upper ends abut against the ends 16 of side plates 10, while the plates 10 can tilt until the tongues 14 abut against the lower halves of the side walls 36 of slots 34 of plates 11. The fulcrums formed by the lugs 20 and the ends 26 of screws 25 permit the side and end plates to adjust themselves automatically to correspond to the shape of the mold. It will thus be seen that the same jacket may be used for straight-sided as well as for tapered molds and that the need for

the two different types of slip jackets heretofore required, is obviated. Moreover, the jacket accommodates itself to and flexibly engages the sides of the mold. The mold does not have to be forced to fit the jacket as has been the case with previous constructions where the jacket is made in one piece or with parts bolted together.

After the casting has been poured, the jacket may be stripped from the mold and used to hold another mold during pouring as in conventional practice. When it is desired to disassemble the slip jacket, as for storage purposes, all that is required is to loosen and remove the screws 25 and pass the tongues 14 back through the slots 34 of the end plates 11. This takes but a moment. When disassembled, the slip jackets consist simply of four substantially flat plates that take but little space in storage and can easily be shipped flat. A jacket made according to this invention, then, will occupy much less space than any known form of slip jacket.

Slight variations in dimensions of the mold may be compensated for by adjustment of the locking screws 25.

Both side and end plates may be made in many different lengths and any length of side plate may be used with any length of end plate. Hence, different sizes of slip jackets can readily be made up in the foundry at a moment's notice as required for molds of different dimensions. Thus, the cost of the equipment that must be kept on hand is reduced, and storage space is saved.

The end and side plates may be cast. They may be made of steel, iron, aluminum, or any other suitable material. Practically no machining is required in their manufacture. All that is really needed is the drilling of the four holes for the four screws 25. Thus, the slip jackets of the present invention can be made very cheaply.

While the invention has been described in connection with a particular embodiment thereof, it will be understood that it is capable of further modification, and this application is intended to cover any variation, uses, or adaptations of the invention following, in general, the principles of the invention and including such departures from the present disclosure as come within known or customary practice in the art to which the invention pertains and as may be applied to the essential features hereinbefore set forth and as fall within the scope of the invention or the limits of the appended claims.

Having thus described my invention, what I claim is:

1. A mold jacket comprising a pair of side plates and a pair of end plates, each side plate having a tongue at each end projecting from the plate between the top and bottom thereof, each tongue having a lug formed thereon and projecting laterally to the outside thereof, each end plate having a slot adjacent each end, each of said slots being of greater width than the combined thickness of a tongue and lug so that a tongue with its lug may be passed through the slot, each of said slots having one bounding side which extends in the direction of height of the end plate and another bounding side which for one half of its height is parallel to the first-named side and for the other half of its height diverges from the first-named side, and a screw threaded into each lug to seat against a part of the end plate adjacent to the slot through which the lug has been passed, to lock the tongue, of which the lug is a part, in the slot to secure a side and an end plate together, the inner end of the screw, which en-

gages the end plate being formed to act as a fulcrum to permit the plates to pivot on one another to accommodate themselves to the shape of the mold.

2. A mold jacket comprising a pair of side plates and a pair of end plates, each side plate having a tongue at each end projecting from the plate between the top and bottom thereof in prolongation of the side plate, each tongue having a lug formed thereon and projecting laterally to the outside thereof, each end plate having a slot adjacent each end, each of said slots being of greater width than the combined thickness of a tongue and lug so that a tongue with its lug may be passed through the slot, each of said slots having one bounding side which extends in the direction of the height of the end plate and another bounding side which for its upper half is parallel to the first-named side and for its lower half diverges therefrom, each side plate having the portions of its end walls, which are above its tongues, diverging from the top of the end plate downwardly and the portions of its end walls which are below its tongues, extending in the direction of its height, and a screw threaded into each lug at an angle of forty-five degrees to seat against a part of the end plate adjacent to the slot, through which the lug has been passed, to lock the tongue, of which the lug is a part, in the slot to secure a side and an end plate together, the seating end of each screw being conical, and the two lugs of each side plate being rounded at their confronting sides to seat against the adjacent portions of the associated end plate, whereby the screws and lugs may act as fulcrums to permit the plates to pivot on one another.

3. A mold jacket comprising a pair of side plates and a pair of end plates, each side plate having a tongue at each end, each end plate having a slot adjacent each end through which

one of the tongues may be passed, and a screw threaded into each tongue in a direction inclined both to the side plate, through the tongue of which it is threaded and to the end plate through the slot of which it passes, to engage the said end plate to lock the said side plate and the said end plate together.

4. A mold jacket comprising a pair of side plates and a pair of end plates, each side plate having a tongue at each end, each tongue having a lug formed thereon which projects laterally to the outside thereof, each end plate having a slot adjacent each end through which one of the tongues with its associated lug may be passed, and a screw threaded into each lug in a direction inclined both to the side plate, through the lug of which it is threaded, and to the end plate, through the slot of which it passes, to engage the said end plate to lock the said side plate and the said end plate together, each of said lugs being shaped to form a fulcrum on which the associated end plate may rock to permit the jacket to accommodate itself to the shape of the mold.
